CLAIM

The ornamental design for a bonnet for agricultural working machine, substantially as shown and described.

DESCRIPTION

FIG. 1 is a front perspective view of a bonnet for agricultural working machine showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof; and,

FIG. 8 is a rear cross sectional view taken along line 8—8 in FIG. 6.
